UNITED STATES PATENT OFFICE

WILLIAM C. RASTETTER, OF FORT WAYNE, INDIANA

FOLDING CHAIR

Application filed September 29, 1930. Serial No. 485,009.

This invention relates to improvements in folding chairs, and the object thereof is to provide a folding structure of its class constituted of few parts that is so constructed as to afford a maximum of rigidity, and the fore and rear legs of which are relatively locked when the legs and seat are in position for use.

An illustrative embodiment of the invention is shown in the accompanying drawings, in which:—

Fig. 1 is a side elevation of a structure in which the invention is embodied, the chair being in extended position and a portion 15 thereof being broken away;

Fig. 2 is a front elevation of the chair in folded position; and

Fig. 3 is a rear elevation of the chair in extended position for use.

The chair shown in the illustrative embodiment of the invention is comprised of a main frame having side members 1 which constitute forelegs, and an upper portion 2 connecting said forelegs in which is secured a back-rest 3. In said forelegs is secured in horizontal position a seat-rod 4, and upon said seat-rod is pivotally supported a seat-frame 5 preferably formed of a single wooden strip bent so as to have parallel side members 6 in which is permanently secured a seat 7 that may be upholstered if so desired. Upon the seat-rod 4 between the side members 6 is disposed a tube 8 encompassing it which constitutes a spacer that prevents inward relative movement of said side members and upon said rod 4 between each side of the seat-frame and the adjacent foreleg 1 is also positioned a tubular spacer 9, which tubular spacers prevent lateral movement of the seat-frame relative to said forelegs on the rod.

To each foreleg 1, upon the inner face thereof, at a point above the seat rod, is pivoted, as indicated by 10, a rear leg 11, and each rear leg is connected with the corresponding side member 6 of the seat-frame by a link 12, one end of each link is pivoted to the seat as indicated by 13, and its opposite end is pivoted to the corresponding rear leg, as indicated by 14.

The forelegs 1 are connected together and held fixedly in spaced relation with each other by a cross-brace 15, and the rear legs 11 are similarly held in spaced relation by a cross-brace 16. The upper end of each arm 17 of the rear leg cross-brace has a perforated U-shaped extension 18 in which a corresponding rod 19 has sliding movement. The upper end of each rod is bent at right angles and extends through the rear end of the corresponding side member 6 of the seat-frame and its lower end has a head 20 made thereon that comes into contact with the lower end of the U-shaped extension of the corresponding arm 17 of the cross-brace 16 so as to limit unfolding movement of the seat-frame. These rods also, when the occupant is seated upon the chair, being engaged at their lower ends by contact of their heads 20 with said extensions 18 which are secured to the rear legs a substantial distance downwardly from the seat-frame, tends to stabilize the rear leg structure so that lateral strain thereof occasioned by swaying movement of the occupant is thereby resisted and the staunchness of the rear leg structure enhanced.

One of the features of the invention is the arrangement of the links 12 in their connections with respect to the side members 6 of the seat-frame and the corresponding rear legs so that their pivotal points are located substantially when the chair is unfolded and in position for use, in alinement with the seat-rod 4 whereby the forelegs and rear leg structure are locked in extended position so that movement of the fore and rear legs toward or from each other is prevented and their extended positions are maintained until the seat-frame is folded. Thus, folding of the rear leg structure is dependent upon folding movement of the seat-frame.

While the invention has been described with particular reference to the illustrative embodiment, it will be understood that the invention may be variously modified and embodied within the scope of the claims.

I claim:—

1. In a folding chair, a main frame constituting a back and forelegs; a seat-rod secured in said forelegs; a seat-frame having 100

a seat thereon, said seat-frame being pivotally supported on said seat-rod; rear legs pivoted at their upper ends to the main frame at points above the seat-rod; links connecting 5 said rear legs respectively with the corresponding sides of the seat-frame at points thereon back from said seat-rod; members secured respectively to said rear legs at points thereon below said seat-frame; and rods pivotally connected with the rear end of said seat-frame and having limited sliding movement in the corresponding members.

2. In a folding chair, a main frame constituting a back and forelegs, a seat including a frame therefor pivotally connected between said forelegs; a rear leg structure pivotally connected with said main frame; links connecting said rear leg structure with the frame of the seat respectively at points 10 located on the seat between the rear end thereof and the pivotal connections of the seat-frame and forelegs whereby limited unfolding movement is imparted to the rear leg structure as the seat is unfolded; and rods 15 pivotally connected with the rear end of said seat-frame and having limited sliding movement in the rear leg structure whereby unfolding movement of the seat is limited.

3. In a folding chair, a main frame having 20 side members constituting forelegs; a folding seat having a frame pivotally supported by said forelegs; a folding rear leg structure pivotally connected with said forelegs and having linked connections with said seat-frame by which unfolding movement of the 25 rear leg structure is limited; and rods connected with the rear end of the seat-frame at points spaced rearwardly from the pivotal support for said seat-frame and having sliding movement in the rear leg structure and provided with heads on their lower ends adapted to limit unfolding movement of said seat frame.

4. In a folding chair, a main frame constituting a back and forelegs; a folding seat member pivotally supported in connection with said forelegs; a folding rear leg structure pivotally connected with said forelegs; linked connections between the rear leg structure and the seat member; and sliding connections between said seat member and lower portion of the rear leg structure provided with heads at their lower ends adapted to limit unfolding movement of said seat member and rear leg structure.

5. In a folding chair, a main frame constituting a back and forelegs, a folding seat member pivotally supported in connection with said forelegs; a folding rear leg structure pivotally connected with said forelegs and having operative connections with said seat-frame by which unfolding movement of the rear leg structure is limited; and rods connected at their upper ends with said seat-frame at points spaced rearwardly from the

pivotal support for the seat-frame and having sliding connections in the rear leg structure at points therein spaced below said seat-frame provided with heads adapted to limit unfolding movement of the seat-frame. 70

In testimony whereof I affix my signature.
WILLIAM C. RASTETTER.
